J. Sutton,

Lubricator

No 12,290.

Patented Jan 23, 1855.

Fig. 1.

Fig. 2.

UNITED STATES PATENT OFFICE.

JOHN SUTTON, OF NEW YORK, N. Y.

LUBRICATOR FOR STEAM MACHINERY.

Specification of Letters Patent No. 12,290, dated January 23, 1855.

To all whom it may concern:

Be it known that I, JOHN SUTTON, of the city, county, and State of New York, have invented a new and useful improvement in 5 grease-feeders for lubricating the cylinders, valve-seats, and other parts of steam-engines, and other apparatus subject to an internal pressure greater than the atmosphere without stopping their operation; and 10 I do hereby declare that the following is a full, clear, and exact description of the same, reference being had to the accompanying drawing, forming part of this specification, in which—

15 Figure 1, is a section through the center of a grease cock constructed according to this invention, which, to distinguish it from another invention of mine for the same purpose I will denominate No. 2. Fig. 2, is an 20 outside view of the piston detached from the feeder.

Similar letters of reference indicate corresponding parts in both figures.

This invention consists firstly in the arrangement of the cylinder and piston which 25 is employed to inject the oil or grease into the part of the engine or apparatus requiring to be lubricated, within or in the bottom of the reservoir or vessel containing the 30 oil or grease, whereby the feeder is rendered much more compact and simple than other feeders acting on a similar principle.

It consists secondly in a certain arrangement of valves whereby the feeder is charged 35 with oil or grease and discharged into the engine or apparatus by simply moving its piston once back and forth.

To enable those skilled in the art to make 40 and use my invention I will proceed to describe its construction and operation.

A, is a reservoir; B, the cylinder and C, the piston. The reservoir is supplied with oil at the top, through openings b, b, in the bottom of a small cup a, into which the oil 45 is poured. This cup forms a covering to protect the oil in the reservoir from dirt. The cylinder B may be cast with or fitted into the reservoir, being placed in the center of the bottom. It may stand up within the 50 body of the reservoir as shown in the drawing, or be entirely below it, but is preferable that it should stand up some distance above the bottom of the reservoir in order that a space may be left around it for the collection 55 of sediment, to prevent any dirt entering the cylinder to interfere with the valves

or to injure the surfaces to be lubricated. The upper end which enters the reservoir is open, and from the lower end leads the passage c, through which oil is ejected from the 60 reservoir against the pressure of steam or other motive agent. At the entrance to the passage c, there is a valve d, which will be closed by the pressure of steam, but has a spring e, applied to it, to prevent its opening 65 and allowing the escape of oil when the engine or apparatus is not in operation. The piston C, is hollow and furnished with a valve f, which opens downward or toward the discharge end of the cylinder. This 70 valve has a spring g, applied to close it. The piston rod h, works through a guide i, in the center of the top of the reservoir and is furnished with a knob or handle outside. At a suitable distance above the piston, an 75 india rubber or other spring j, is attached to the rod in order to serve as an elastic stop to arrest the upward movement or retraction of the piston. The guide i, is intended to serve as a vent in filling the reservoir and 80 therefore it should reach above the top of the cup a, and the piston rod should fit it easily.

The oil is fed by simply retracting the piston by hand from the discharge end toward the entrance of the cylinder and then returning it. The piston is shown in Fig. 1, in black outline in the act of retraction and in red outline in the act of returning. The retraction of the piston causes a vacuum 90 to be formed in front of or below it and thus causes the valve f, to open, and the oil to rush from the reservoir through the piston, as indicated by the black arrows in Fig. 1, the valve d, in the mean time remaining 95 closed. The return of the piston causes the valve f to close and the valve d, to open, and the oil below or in front of the piston to be ejected through the passage c.

The arrangement of the cylinder and piston of the feeder within the reservoir with a guide for the piston rod in the top of the reservoir not only makes the feeder more compact but simplifies the construction. The arrangement of the two valves in the piston and discharge end of the cylinder enables the oil to be fed while the engine is running by one movement back and forth of the hand of the engineer which in locomotive engines is a great advantage. All 100 other feeders for a similar purpose known to me require at least two movements either 105 110

to open and close two cocks or to open and close one cock or stopple and move the piston.

What I claim as my invention and desire 5 to secure by Letters Patent is—

1. Arranging the cylinder B and piston C, of the feeder within or in the bottom of the grease reservoir A, with the cylinder opening directly into the reservoir substantially as described whereby the construction 10 of the feeder is simplified and it is rendered more compact, and provision is made for collecting the sediment within the reservoir.
2. Constructing the feeder with a valve f,

in the piston opening toward the discharge 15 end of the cylinder, and a valve d, in the discharge end of the cylinder, opening against and closing with the pressure of the steam or motive agent substantially as described, whereby it is caused to be only 20 necessary to move the piston once back and forth to charge and discharge the feeding cylinder, and the lubrication is effected more quickly and with less trouble to the engineer.

JOHN SUTTON.
